DESIGN FOR SUNGLASSES

Frances A. Renthcler, Mamaroneck, N. Y.

Application January 9, 1937, Serial No. 66,967

Term of patent 7 years

To all whom it may concern:

Be it known that I, Francis A. Renthcler, a citizen of the United States of America, residing at Mamaroneck, county of Westchester, State of New York, have invented a new, original, and ornamental Design for Sunglasses, of which the following is a specification, reference being had to the accompanying drawing, forming part thereof.

The figure of the drawing represents a perspective view of sunglasses showing my new design.

The dominant features of this design are the absence of frame for the eye members and the forward portions of the temples enlarged to approximately the height of the eye members. At least the enlarged portions of the temples are transparent.

I claim:

The ornamental design for sunglasses, as shown and described.

FRANCES A. RENTCHLER.
